(57) **CLAIM**

The ornamental design for a machine for making ice cream, as shown and described.

DESCRIPTION

FIG. 1 is a front right perspective view of a machine for making ice-cream, according to the invention;

FIG. 2 is a front left perspective view thereof;

FIG. 3 is a front view thereof;

FIG. 4 is a right side view thereof;

FIG. 5 is a left side view thereof;

FIG. 6 is a top view thereof;

FIG. 7 is a front left perspective detail view thereof, with the unclaimed subject matter removed for ease of illustration;

FIG. 8 is a front right perspective detail view thereof, with the unclaimed subject matter removed for ease of illustration;

FIG. 9 is a bottom detail view thereof, with the unclaimed subject matter removed for ease of illustration; and,

FIG. 10 is a back detail view thereof, with the unclaimed subject matter removed for ease of illustration.

Any broken lines in the figures illustrate portions of the machine that form no part of the claimed design.
